FURNACE CLOSURE

John G. Hoop, Pittsburgh, Pa., assignor to Westinghouse Electric & Manufacturing Company, East Pittsburgh, Pa., a corporation of Pennsylvania

Application November 16, 1938, Serial No. 240,654

14 Claims. (Cl. 110—173)

My invention relates broadly to a furnace closure construction of general utility, but of particular application to heat treating furnaces in which a charge can be heat-treated while enveloped by an appropriate protective, gaseous atmosphere.

Treating processes of this character are well known, and the composition or constituents of the protective gas are determined by the particular charge being heat-treated, and the process of heat treatment to which it is being subjected. Dissociated ammonia, or partially or completely burned hydro-carbon gases, are among the most common of the protective atmospheres utilized.

Where protective gases are employed, their entire efficacy may be destroyed if outside air were permitted to leak into the heating chamber of the furnace. In order to prevent or limit such leakage, the gaseous atmosphere within the furnace is maintained at a pressure slightly above atmospheric whereby a plenum system obtains in the furnace. The greater pressure of the protective atmosphere now causes the latter to leak out through any cracks or openings in the furnace that are not perfectly sealed, and a small amount of leakage of protective atmosphere from the inside of the furnace outwardly is desirable in order to prevent outside air leakage into the furnace. However, leakage is necessarily a source of continuous waste and expense, and, therefore, furnace structures of the type described seek to minimize or decrease the leakage to as small an extent as possible. My invention is directed to improving the seal between that part of the furnace which requires an opening in a furnace wall, and the door therefor.

In accordance with the preferred embodiment of my invention, a furnace door is provided having an outer shell of relatively thin, preferably flexible metal, such as sheet metal, and to the edges of this shell is secured a door rim, one face of which serves to abut a suitable door frame about a charge entrance or exit opening, as the case may be, in the furnace wall. The rim and frame are made of heavy material, preferably steel, to resist warping, and their abutting or mating faces are, in my preferred embodiment, ground flat so that, in effect, a tight joint results which prevents any appreciable leakage of the gaseous atmosphere.

As additional precautions to prevent destruction of the efficacy of the seal by warpage of the rim and frame, the door frame is protected from the direct heat of the furnace by embedding it in

the furnace wall some distance from the furnace opening, while the rim of the door is protected by the novel door construction I employ.

It is, accordingly, among the broad objects of my invention to provide a door seated against its door frame so that, in effect, the two comprise a tight seal, and to provide a door construction whereby the possible warpage of the door does not disturb the aforesaid seal.

My invention includes also many novel features incorporated into a construction for the furnace door. As previously described, the outer shell of the door is of a relatively thin metal to which is secured the rim. Also secured to the shell, but inwardly of the rim, are rigid members associated into a rigid inner frame for the door, the members being in the form of steel channels which also support and interlock the tile of the door, and a layer of deformable insulation is adjacent the side walls. Any warpage of the rigid members, therefore, merely deforms the loose insulation, and in extreme cases may deform parts of the shell, but such deformations will not be transmitted to the rim.

Since the component parts of my door can be easily shaped or obtained from standard stock, the door lends itself readily to fabrication and can be built to any desired size and shape without entailing large expenses that would be incident to the casting of the doors in small quantities.

Other objects and novel features of my invention will be apparent from the following description thereof, taken in conjunction with the drawings, in which

Figure 1 is a fragmentary sectional vertical view of a furnace wall having an opening therefor built in accordance with the preferred embodiment of my invention, the closure for the opening being shown diagrammatically.

Fig. 2 is a fragmentary elevational view of the door frame looking at it from outside of the furnace.

Fig. 3 is an elevational view, on a larger scale, of the door as seen from the furnace side;

Fig. 4 is a horizontal sectional view on the line IV—IV of Fig. 3; and

Fig. 5 is a vertical sectional view on the line V—V of Fig. 3.

My invention is applicable to any suitable type of furnace, one wall only of which it is deemed necessary to show in order to describe the essential features of my invention. The furnace comprises a wall 2 having an opening 4 through which a charge may pass. The furnace walls are encased in an outer metallic shell 6, impervious to

gas, as is customary in the construction of furnaces in which protective gaseous atmospheres are utilized.

It may be observed that the shell 6 terminates somewhat short of the opening 4, and along the cut-out edges has secured thereto, as, for example, by welding, a re-enforcing backing frame 8 which serves as a securing base for the door frame to be subsequently described. The opening 4 is actually formed by a surrounding layer of refractory tile 10 suitably set to project outward beyond the aperture in the shell 6 for the purpose of protecting a door frame 12 from the direct heat within the furnace. The tile 10 is suitably shaped to provide a seat 14 for the frame 12 which, however, is supported and maintained in position by means of bolts 16 extending through holes spaced at suitable intervals about the frame and secured in re-enforcing plate 8.

Secured to the bottom of the frame by means of the lower bolts 16 is a door rest 18, which serves as a rest for a door 20. Suitable positioning lugs 22 are fastened to the ends of the door rest in order to confine the door to a predetermined position relative to the door frame 12.

The furnace wall 2 is so constructed that the frame 12 in its normal position will be at a slight angle inward of the vertical so that the door 20 resting upon the rest 18 will be forced by its own weight against the door frame 12. It is preferable to have the rest 18 assist this automatic sealing action and, to this end, the rest 18 comprises a protruding side 24 substantially perpendicular to the frame 12.

In accordance with my invention, the door comprises an outer shell 26 formed of sheet metal, which, for the door of the particular embodiment shown, is of a box-like shape with upper and lower sides 28 and 30, respectively, and vertical sides 32. The shell may be formed of the sheet metal in any suitable manner to any suitable shape, but care should be taken that the outside periphery 34 conforms substantially to the shape of the bottom of a door rim 36 secured thereto. The door rim 36 conforms in contour to the door frame 12 and is preferably of heavy steel stock. The outer surface of the furnace door therefore comprises the door rim 36 and the outer shell 26. The shell 26 may be formed of a single sheet of metal or of a plurality of sheets suitably secured in a gas-tight manner, although I prefer to employ a single sheet shaped by bending or otherwise to the desired configuration. The door rim 36 is also secured to the shell 26, preferably by welding, so that the entire door structure is impervious to gas.

In order to lend a certain amount of rigidity to the door and also to support the refractory and insulating material thereof, suitable frame members are fastened to the shell inwardly of the door rim 36, and may take the form of channel members with their channels directed toward the center of the door. The channel members are preferably secured to, what may be called for the purposes of identification, the upright bottom 40 of the shell 26.

A lower channel member 42 is secured to the bottom 40 by means of bolts 44, although any other suitable securing means may obviously be employed, and in such manner that the inside leg 46 and the outside leg 48 of the channel member extend away from the adjacent part of

the rim 36. As many additional re-enforcing channels may be added to the door as the weight of the door may require, and in the particular embodiment, an upper channel 50 and side channels 52 and 54 complete a rectangular re-enforcing and supporting frame for the door, being secured substantially gas-tight to the bottom 40 by bolts, such as 44.

The channel members 42, 50, 52 and 54 are assembled to form the supporting frame which is similar in shape to the door rim 36, but spaced from the inner periphery to provide a space that is filled with a deformable insulating material 56 comprising, for example, a mixture of asbestos and an insulating diatomaceous substance. Suitable insulating bricks 58 are placed adjacent the bottom wall 40 inward of the channels, and refractory tiles 60 complete the door structure. From another aspect, my invention may be considered as including a framework comprising the channel members 42, 50, 52 and 54, which act as rigid side members. In such case, the shell 26 forms a gas-tight connection between the side members and the rim 36.

The lower channel 42 serves as the main support for the refractory and firebrick in the door, and to further maintain the rigidity of the channel member, especially when subjected to high temperatures, a plurality of gusset plates 62 may be welded to the channel at suitably spaced intervals. These gusset plates preferably conform to the cross section of the inside of the channel, except that the upper edge slopes downward substantially from the top of the leg 48 to the middle of the leg 46, as shown more particularly in Fig. 5.

The refractory tile 60 is suitably formed to rest within the channel frame, being somewhat interlocked in position by the centrally-projecting legs of all of the channel members.

To provide a ready means for raising and lowering the door and for holding it in position, a plate 64 is tack welded or otherwise secured to the top side 28 of the outer shell, and to this plate at suitably spaced points are secured cable fastening structures 66 whereby the door may be raised and lowered by means of cables, not shown, secured to pins 68 and riding over pulleys in a customary manner, suitable guides being provided for the door.

It is a primary purpose of my invention to provide an effective seal between the door and its frame, and to this end, the frame 12, as well as the rim 36, are both of rather substantial stock, sufficiently heavy to resist warping to a large degree. The frame and rim may be annealed, if desired, to remove all internal stresses and their mating faces subsequently ground flat to assure adhesive mating surfaces between them. An effective seal is thus obtained since the ground faces of the rim and frame will mate each other so closely as to decrease to a negligible amount the leakage of any gas from inside the furnace to the outside through the seal.

It may be observed that the refractory tile 10 forming the opening 4 of the furnace is so formed as to be interposed between the frame 12 and the radiant interior of the furnace. The rim 36 rests upon the frame 12 in such manner that their inner peripheries substantially align, and, therefore, the inner rim 36 is also protected from the radiant heat of the furnace by the tile 10.

Conduction of heat to the rim 36 from the

door parts exposed to the interior heat of the furnace is reduced to substantially negligible amounts by the insulation 56 which compels the conduction path of heat from the exposed legs of the channels to extend to the outer shell 26 at a point removed from the rim 36. Any conduction heat, therefore, is thoroughly dissipated by the outside shell 26 before reaching the rim 36.

It may, therefore, be seen that by my construction the amount of heat that can reach the door frame and door rim is substantially reduced. In addition, the door frame and rim are made, as aforesaid, of heavy stock, and the combination of minimizing the heat flow to the parts, together with their mass exposed to the cool outside, make the possibility of their warpage, and, therefore, the destruction of the efficacy of the seal between them, remote. In this connection, it may be observed that the frame 12 is considerably larger than the rim 36 to the end that both the rim and the frame will have a large surface area for dispelling to the surrounding cooling atmosphere whatever heat reaches them.

The channel members 42, 50, 52 and 54 are, of course, subjected to the heat of the furnace, which, if operated at elevated temperatures, may be quite intense. These channels, therefore, may have a tendency to warp with continued use. To reduce this tendency the channels' sides toward the furnace are slotted at suitable intervals along their length to an extent approximately half their width. Such slots 70 preferably extend somewhat beyond the depth of the refractory tile 60, since the latter is only semi-insulating and by making the slots extend beyond them, warpage and distortion due to differential heating are decreased.

The slots also prevent excessive permanent distortion of the channels but, nevertheless, it may be observed that if the channels should become distorted, whether permanently or not, the flexibility of the outer shell 26 and the deformability of the insulation 56 will absorb the deformations before they can be transmitted to the rim 36. The bent corners between the bottom 40 and the sides 28, 30 and 32 of the shell materially aid the adaptability of the door to deformations of the exposed parts by being capable of a change in angle. Additionally the shell 26 is obviously capable of deformation. If desired any suitable clamping means may be employed to hold the rim securely against the door frame. Thus, eccentric cams can be employed for this purpose, as well known to the art, or the door guides (not shown) may be made sufficiently close fitting for the purpose.

As an added refinement of my invention, I prefer to have the rim 36 protrude slightly beyond the inner, exposed surface of the remainder of the door, so that the door rim will always bear on the door frame.

It may, therefore, be observed that in accordance with my invention I have provided a closure for satisfactory use with high temperature furnaces employing a protective gaseous atmosphere, and which may be simply and economically fabricated.

While I have described my invention in a preferred embodiment, it is obvious that changes may be made and equivalents applied thereto.

I claim as my invention:

1. A furnace door structure comprising a heavy rim, a metallic deformable shell secured

to said rim, an inner, substantially rigid frame within said shell and secured thereto, slightly deformable insulation material between said inner frame and shell, a layer of insulation material within the frame and adjacent said shell, and an exposed layer of refractory material in front of said insulation material, and held in position by said frame.

2. A furnace door comprising a metallic box having a wide, heavy, open rim and a shell secured to said rim, deformable insulating material adjacent said rim inwardly thereof, said shell having parts made of deformable material, reenforcing means within said box, insulating and refractory material within said box and substantially completely filling the remaining space therein, said reenforcing means forming a support for the last said material, and comprising rigid structural steel members, said steel members being slotted at spaced intervals along the inner or furnace-facing parts thereof.

3. A furnace door adapted to be vertically disposed comprising a wide, heavy, open rim and a shell secured to said rim, deformable insulating material adjacent said rim inwardly thereof, said shell having parts made of deformable material, reenforcing means within said box, insulating and refractory material within said box and substantially completely filling the remaining space therein, said reenforcing means comprising a rigid, two-legged steel member near the lower end of the door and having one leg secured to the shell and the other leg extending upwardly to form a supporting means for the last said material.

4. A furnace door adapted to be vertically disposed comprising a wide, heavy, open rim and a shell secured to said rim, deformable insulating material adjacent said rim inwardly thereof, said shell having parts made of deformable material, reenforcing means within said box, insulating and refractory material within said box and substantially completely filling the remaining space therein, said reenforcing means comprising a rigid, two-legged steel member near the lower end of the door and having one leg secured to the shell and the other leg extending upwardly to form a confining interlock for the last said material, said other leg being slotted at intervals.

5. A furnace door adapted to be vertically disposed comprising a wide, heavy, open rim and a shell secured to said rim, deformable insulating material adjacent said rim inwardly thereof, said shell having parts made of deformable material, reenforcing means within said box, insulating and refractory material within said box and substantially completely filling the remaining space therein, said reenforcing means comprising a rigid, two-legged steel member near the lower end of the door and having one leg secured to the shell and the other leg extending upwardly to form a support and confining interlock for the last said material, said other leg being slotted at intervals, and gussets reenforcing said steel member.

6. A furnace door comprising a metallic box having a wide, heavy, open rim and a shell secured to said rim, deformable insulating material adjacent said rim inwardly thereof, said shell having at least a part made of flexible sheet metal, reenforcing means comprising structural members within said shell, insulating and refractory material within said shell and substantially completely filling the remaining space

therein, said reenforcing means forming a support for the last said material, and generally following the contour of said rim, said structural members being substantially the depth of the door, secured to said shell at one end, and having inwardly projecting legs at their other ends, whereby to aid in retaining the last said material in said shell.

7. A furnace door comprising a metallic box having a wide, heavy, open rim and a shell secured to said rim, deformable insulating material adjacent said rim inwardly thereof, said shell having at least a part made of flexible sheet metal, reenforcing means comprising structural members within said shell, insulating and refractory material within said shell and substantially completely filling the remaining space therein, said reenforcing means forming a support for the last said material, and generally following the contour of said rim, said structural members being substantially the depth of the door, secured to said shell at one end, and having inwardly projecting legs at their other ends, whereby to aid in retaining the last said material in said shell, said leg parts of said members being slotted at intervals.

8. A furnace door comprising a metallic box having a wide, heavy, open rim and a shell secured to said rim, deformable insulating material adjacent said rim inwardly thereof, said shell having at least a part made of flexible sheet metal, reenforcing means comprising structural members within said shell, insulating and refractory material within said shell and substantially completely filling the remaining space therein, said reenforcing means forming a support for the last said material, and generally following the contour of said rim, said structural members being substantially the depth of the door, secured to said shell at one end, and having inwardly projecting legs at their other ends, whereby to aid in retaining the last said material in said shell, said leg parts of said members being slotted at intervals, and gusset means for the bottom of said members.

9. A furnace door comprising a metallic box having a wide, heavy, open rim and a shell secured to said rim, insulating material adjacent said rim inwardly thereof, said shell having at least a part made of flexible sheet metal, reenforcing means within said box, and insulating and refractory blocks within said box and substantially completely filling the remaining space therein, said reenforcing means forming a support for the said blocks.

10. A furnace door comprising a metallic box having a wide, heavy, open rim and a shell se-

cured to said rim, insulating material adjacent said rim inwardly thereof, said shell having at least a part made of flexible sheet metal, reenforcing means within said box, and insulating and refractory blocks within said box and substantially completely filling the remaining space therein, said reenforcing means forming a support and interlock for the said blocks and following the contour of said rim.

11. In combination with a metal-encased furnace having a wall with an opening through which a charge may pass, a door frame about said opening, said wall being constructed to space said frame from said opening, said frame being of metal and having a closure-seating face, a closure for said opening, said closure including refractory tile, and having a rim with a face for mating the said closure-seating face whereby the two will seat together snugly to form a substantially gas-tight seal, means forming part of said closure for insulating said rim from the heat of the furnace, means in said closure for supporting said refractory tile, said last means being inward of said rim, and said closure comprising an outside, flexible metallic shell whereby warping of said last means does not affect said rim.

12. A furnace door structure comprising a framework having relatively rigid side members, a rim about said framework and spaced from said side members, insulating material within said framework, substantially gas-tight means securing said rim to said framework, and insulation between said gas-tight means and said side members.

13. A furnace door structure comprising a framework having relatively rigid side members, a rim about said framework and spaced from said side members, insulating material within said framework, substantially gas-tight means securing said rim to said framework, insulation between said gas-tight means and said side members, said gas-tight means being deformable whereby warping, expansion or contraction of said side members will not appreciably affect said rim.

14. A furnace door structure comprising a framework having relatively rigid side members, a rim about said framework and spaced from said side members, insulating material within said framework, substantially gas-tight means secured to said rim and framework, and insulation between said gas-tight means and said side members, said framework side members being slotted at intervals along the edges facing the furnace.

JOHN G. HOOP.
